UNITED STATES PATENT OFFICE.

GEORGE A. WHEELER, OF BROOKLYN, NEW YORK.

MOVING STAIRWAY.

No. 888,949.

Specification of Letters Patent.

Patented May 26, 1908.

Application filed February 21, 1906, Serial No. 302,230. Renewed October 18, 1907. Serial No. 398,033.

To all whom it may concern:

Be it known that I, GEORGE A. WHEELER, a citizen of the United States, residing at Brooklyn, New York city, New York, have 5 invented certain Improvements in Moving Stairways, of which the following is a specification.

The main object of my invention is to so construct a moving stairway consisting of 10 an endless chain of step sections and guides therefor, that the same series of step sections can be used to carry passengers on the elevating run as well as on the return run, the step sections always remaining right side up.

15 A further object of the invention is to provide rectangular treads and symmetrical risers, and to obviate irregular steps on the carrying portion of the stairway, and also to avoid folding step sections.

20 A still further object of the invention is to so construct the stairway that the looped portion will be concealed or protected so that it will not be used as part of the carrying portion of the stairway. I prefer to depress the 25 looped portion so that it can run under a fixed platform.

My invention also relates to certain details which will be described hereafter.

In the accompanying drawings:—Figure 1, 30 is a plan view of my improved moving stairway; Fig. 2, is a diagrammatic view on the line 2—2, Fig. 1; Fig. 3, is a diagrammatic view, showing the depressed loop, on the line 3—3, Fig. 2; Fig. 4, is an enlarged longitudinal sectional view showing the upper portion of the stairway; Fig. 5, is a plan view of Fig. 4; Fig. 6, is a section on the line 6—6, Fig. 5; Fig. 7, is a plan view on a reduced scale showing one of the turns and one step 35 section underlying the other at the turn; Fig. 8, is a diagram view illustrating the position of the steps at the turn in full line and the position of the steps on the carrying run in dotted line; Fig. 9, is a detail view of one 40 section of the step sections partly in section, showing the connection; Fig. 10, is a diagrammatic view showing a platform in the mid-position between the upper and lower fixed platforms; Fig. 11, is a view of a portion of the step 45 sections at the turn; Fig. 12, is a detail sectional view through the step connections; Fig. 13, is a detail perspective view of one of the hubs; Fig. 14, is a detached sectional view 50 of one of the rack links; Fig. 15, is a sectional

view through the stairway, showing a form 55 slightly modified from that illustrated in Fig. 8; Fig. 16, is a detached view, partly in section, of one of the step sections and connections illustrated in Fig. 15; Figs. 17 and 18, are detail views of portions of Fig. 15; Fig. 19, is a view of a modification showing the ascending carrying run located at right angles to the descending carrying run; Fig. 20, is a diagram sectional view of Fig. 19; Figs. 21 and 22, are views showing the looped 60 sections arranged to turn above the adjacent landings instead of below them as in the other figures; Fig. 23, is a view illustrating a modification of the connecting links; Fig. 24, is a plan view of the connecting links 65 illustrated in Fig. 23; and Fig. 25, is a perspective view of one of the sockets illustrated in Fig. 23.

Referring in the first instance to Figs. 1 to 3, both inclusive, which illustrate one of the 70 simplest forms of my improved stairway, A is the ascending run of the stairway and A' is the descending run of the stairway.

B is the lower platform and B' is the upper platform. The guides for the step sections 80 are so formed that the step sections themselves form part of the two platforms in the present instance, although this is not essential in carrying out my invention.

D is the endless carrier made up of a series 85 of connected step sections, preferably of the form clearly illustrated in Figs. 4 and 5 of the drawings. The tread surface of each step section is rectangular and the risers are symmetrical, and the step sections of the carrying 90 portion of the stairway are held rigidly in proper position, the edge of one section abutting against the other, so as to close the joints between the step sections and to make the carrying run perfectly rigid. When it is 95 desired to turn the step sections it is necessary to move the step sections so that one will be either below or above the succeeding one in order that it will be free to turn under or over the succeeding step section, as illustrated clearly in Figs. 5 and 7, and in the diagram Fig. 8, and as it is not desirable or necessary to use this portion of the carrier I preferably turn the carrier under a platform or protect it so that it cannot be used. In 100 this specification that portion of the stairway not used as a carrying run is designated by the term "loop."

It will be understood at the outset that I may make as many intermediate platforms, such as shown in Fig. 10, as desired, where several floors are to be connected by a single endless carrier or where it is desired to form a break in the stairway, and it will also be understood that while in Fig. 1, I have shown the ascending and descending carrying sections arranged side by side and the platforms of both on the same level, the platforms of one may be below the platforms of the other and the descending carrying portion may be at any angle desired in respect to the ascending carrying portion, for instance, in Figs. 19 and 20, I have shown the descending carrying portion at a right angle to the ascending carrying portion and the two platforms at a distance apart one from the other. Thus I do not limit myself to the particular type of stairway shown in the drawings, as the type of stairway will depend considerably upon the location.

Referring now to the details of the invention, on each side of the stairway are rails a, a' , Fig. 6, below an overhanging flange a' in the present instance, and mounted in bearings on each step section d is an axle d' having flanged wheels d^2 on each end which travel on the rails a . Guard rails are used at points where it is necessary to hold the wheels to the rails a .

There is a single wheel at each end of each step section which is the sole support for the step sections. I do not rely upon the wheels to hold the tread surfaces of the step sections horizontal but rely upon the enchainment described hereafter.

Projecting from each step section is a post C and on each post is a series of hubs c, c', c^2, c^3 ; these hubs are free to swivel on the post, as shown in Fig. 12, and links i, i' connect the hubs c, c^2 of one step section with the hub c, c^2 of an adjoining step section, while links i^2, i^3 connect the hubs c', c^3 respectively, of one step section with the hubs c', c^3 of a step section on the opposite side. The link i^3 in the present instance has teeth i^4 , Fig. 9, and the link is so shaped as to form a section of what may be termed an endless rack, forming part of the carrier D . Meshing with this rack are one or more toothed wheels H mounted on driving shafts H' , in the present instance I have shown one driving shaft H' mounted just below the upper platform of the stairway, as illustrated in Fig. 4, but it will be understood that any number of driving wheels may be placed in different position according to the character of the stairway and the number of platforms which are formed by the carrier as it travels in the endless path. This link i^3 has a flange i^5 forming a pocket to catch any lubricant which may drip from the post and hubs, as these hubs must be kept lubricated. By this means I am enabled to prevent the drip, to a

great extent, of the lubricant throughout the entire run of the stairway and limit the discharge of the lubricant from the link at certain points, which would be where the greatest tip is given to the link.

As illustrated in Fig. 12, the upper hub c has a lip c^4 for the introduction of lubricant and each of the hubs has oil grooves c^5 , Fig. 13, which carry the lubricant to the arms upon which the several links are hung, thus the joints between the several step sections can be thoroughly lubricated.

The upper links i are preferably curved as shown, so as to clear the step sections when they are on the inclined runs.

Projecting from the underside of each step section and on each side of the post are lugs e, e', e^2, e^3 , the lugs on each side being spaced a sufficient distance apart to allow for sufficient play of arms f, f' , the arm f projects from the hub c between the lugs e, e^2 and the arm f' projects from the second hub c' between the lugs e', e^3 as clearly illustrated in Figs. 5 and 6.

It will be noticed in referring to Fig. 5, that when the step sections are on a straight line the arm f bears against the lug e and the arm f' bears against the lug e' , thus preventing the step sections swinging on the post as a pivot and keeping all the step sections in alignment. When the step sections, however, strike the curve of a loop as on the right hand side of Fig. 5, the arm f' , which is carried by the preceding link, will strike the lug e^3 so that as the enchain links travel around the curve they will hold the step sections in radial positions while turning and the arm f will strike the lug e^2 , and as the step sections are now traveling one below the other, as in Fig. 4, one step section will pass under the succeeding one, allowing the turn to be readily made; the step sections being always under the control of the enchain links and their arms. It will be seen that the arms are not required to guide the step sections into radial position, but act merely to retain them in that position.

As soon as the step sections make the complete turn they are locked by the arms in the same manner as illustrated in the straight portion of Fig. 5.

I preferably make the incline at the loop or turn steeper than the incline of the carrying portion of the stairway, as illustrated in the diagram, Fig. 8, in which the full lines illustrate the incline and the position of the step sections in respect to each other when on the loop portion, and the dotted lines illustrate the relation of the step sections in respect to each other when on the straight or carrying portions of the stairway. It will be seen by the full lines in Fig. 8 that one step section is clear of the other so that it can pass under the same, and by the dotted lines that I preferably arrange the step sec-

tions in this manner so as to make a close fit between the step sections on the carrying run, while at the same time aid the arms in holding the step sections in position while 5 on the carrying run.

Each step has two symmetrical risers, one on each side, preferably convex with a curvature substantially coinciding with the path through which the contiguous edge of 10 the succeeding step swings in relation to it in changing from the position, on the carrying run, in which their tread surfaces are in parallel horizontal planes, to the one in which they are in the same plane, and vice 15 versa. Thus only on straight portions of the guideway do the step sections have clearance to change position with relation to each other as described; and, in order to turn the steps, the part of the loop guideway adjacent 20 to a horizontal portion of the carrying run, in the preferred form, is a straight downward incline, as from Z to Z', Fig. 7, of sufficient length to enable the steps to assume relative 25 positions in which the preceding step is below and free to swing under the succeeding step. After the steps have assumed this 30 relation the preceding step is ready to be turned by the segment of helically curved track that is joined to the straight track. In Figs. 1 and 7 this is a segment of 90°, and it 35 will be noticed that each step may be, and preferably is, in a radial position when it strikes the curve, and by the arms f and f' moving to engage the lugs e and e' respectively, it is retained in radial position while 40 traveling on the curve, and consequently is in such position when it arrives at the end of the spiral segment, the radius of the latter, measured at the center of the steps, being so 45 proportioned with relation to the width of the steps as to produce this result.

The step has now made a quarter turn, and, to make the remaining portion of the turn, it is necessary for the steps to assume a 50 position in which the preceding step is above the succeeding one to enable the former to swing over the latter. Hence the guideway of the loop next consists of straight downwardly and upwardly inclined parts, with an intermediate straight horizontal part, on 55 which the step sections have clearance to assume the described relative positions. Next comes another spiral segment, similar to the first, on which the steps are turned the remaining 90 degrees, and then a straight part joins the loop to the horizontal part of the carrying run, enabling the steps to assume a common level to form a landing. In the form illustrated by Figs. 21 and 22 these 60 conditions are, of course, reversed.

It will be noticed in referring to Fig. 4, that the rail is curved at the point where the inclined carrying portion of the stairway connects with the horizontal platform portion, 65 and that on the opposite side where the step

sections pass under the fixed platform to a position to be turned the joint is at an angle.

This is clearly shown at x, Fig. 11. I also preferably make the joint between the inclined portion and the straight portion, at 70 the base of the incline, angular, as shown at x', Fig. 11. The length of the rail a², which extends from the point x to the point x', is so proportioned that when one wheel is at the angle at the point x', for instance as in 75 Fig. 11, the point x is midway of the wheels of two step sections. This arrangement acts to prevent any jerky movement of the step sections in traveling over the angular portions of the rails, as it compensates for the 80 movement of the links, the point x being midway of the point between the links as the point x' is at the pivot, and vice versa.

In Figs. 4, 6 and 9, I have shown the wheels carried by the body portion of the step sections, whereas in Figs. 15 to 18, both inclusive, I have shown the wheels carried by arms d³ projecting from the body portion of the step section d and the axle d⁴ is carried by a hub d⁵ on the post C, the wheels d⁶ being 90 mounted on the axles and adapted to rails a in a similar manner to that shown in Fig. 6. In either form I may use a side pressure roller d⁷ carried by a swivel box d⁸ on the end of the axle d⁵, as illustrated in detail in Figs. 17 95 and 18. This roller rests against the inner curved portion of the body portion of the stairway and takes considerable pressure off the flanges of the wheels.

The roller is out of contact with the guideway except on the inner part of the loops, and is preferably so mounted and balanced as to normally take the same angle of inclination with respect to the horizontal that the guideway has at the beginning of the loops, 100 and the roller is free to swivel on its journal within the limits necessary to enable it to follow the inclinations of the inner part of the loops. I may also provide a guard rail as shown, for the wheels running on the outer 105 rails of the loops.

In Figs. 23, 24 and 25, I have illustrated a modification of the link connections of my invention. Instead of the links being connected by hubs having short bearings and 110 ordinary perforated links arranged in pairs, I may use a ball and socket construction, as illustrated in said figures. The hubs may be in the form of blocks c⁴, each having a half socket c⁵, the several blocks being connected 115 together and to the step sections d by two rods c⁶. Mounted in these sockets are the balls i⁷ at each end of the links i⁸, the lower link having the rack teeth i⁹ similar to the rack teeth shown in Fig. 14.

The blocks c⁴ have slots c⁷ which are of suitable shape to provide the required clearance for the links, and the vertical sides e⁴, e⁵, e⁶, e⁷ of the slots act as stops and coöperate with the edges of the links to hold them 130

in alinement and prevent lateral movement, similarly to the lugs e , e' , e^2 , e^3 and the arms f and f' of the other form.

While I prefer to construct the stairway so that the step sections will be depressed when making the curve to pass under a fixed platform, I may arrange the mechanism so that the step sections will be elevated at the loop instead of depressed, as shown in Figs. 10, 21 and 22. This elevated portion of the stairway being inclosed or otherwise protected so that it cannot be used as a carrying portion of the stairway. This is done by so arranging the guiding rails at such an angle that a step section will be elevated at a sufficient height to swing over a succeeding step section on the first quarter turn and if a half turn is to be made will swing under the succeeding step section on the last quarter turn, as illustrated in said figures. Thus it will be seen that by my invention I am enabled to make a moving stairway in which the step sections will always remain right side up and which can be turned in a very small space, the straight portion of the stairway being utilized to carry passengers either up or down and the curved or loop portion of the stairway being the only portion that need be protected or covered.

As illustrated in Figs. 1 and 2, the ascending carrying run A is straight, then at the upper platform a quarter turn is made at the same time the step sections are depressed so that the preceding step section can swing under the succeeding step section, then two or more of the step sections are arranged on a level so as to place them in position to make another quarter turn and enable the preceding step section to pass over the succeeding step section. When the full half turn is made the step sections are exposed and preferably arranged so that a flat platform portion is provided, when they pass down the return run A'. At the base of the stairway the step sections make another half turn and connect with the ascending run.

The guides for the step sections are so arranged that there is preferably a horizontal platform composed of step sections at both the upper and lower ends of the ascending and descending runs of the stairway and, as previously remarked, if it is desired to make a break in the stairway, for instance at a floor, if the stairway is built to extend beyond one floor, then the guides may be arranged so that a horizontal platform will be formed of step sections, as illustrated in Fig. 10.

If it is desired to arrange the descending carrying run of the stairway at an angle to the ascending run then, if the angle is a right angle, a quarter turn may only be necessary, as illustrated in Fig. 7. Or a construction may be used as illustrated in Figs. 19 and 20, previously described.

By the above invention it will be seen that I can make a very simple and practical moving stairway, which will take up comparatively little room and will not affect the head room between floors of a building or other structure in which it is erected.

The looped portion of the stairway is preferably concealed under the floor, the number of the steps composing the loop being so few as not to make a noticeable break in the ceiling below the platform, taking up considerably less space than where a single flight stairway is used in which the return run turns under the carrying run.

The loops are preferably covered by the platform used in arching the ascending or descending runs of the stairway and these platforms can be removable so that access can be readily had to all portions of the stairway, consequently any necessary repairs can be quickly and accurately made and the parts can be readily lubricated when necessary.

While I have shown plates spanning the openings where the steps pass under the floors, it will be understood that I may, and preferably would, employ some other well known device for safeguarding passengers at these points.

I do not claim broadly in this application the step sections having the depending posts, hubs and connecting links, with arms and co-operating lugs, as this is fully claimed by me in an application for patent filed October 14th, 1905, Serial Number 282,783, relating to a spiral stairway.

I claim:—

1. A moving stairway having ascending and descending runs, and curved connecting runs arranged on an incline and in part diverging from a single vertical plane, with quadrangular step sections arranged to travel on said runs, substantially as described.

2. The combination in a moving stairway, of endless guides, a series of step sections arranged in an endless chain, said guides having straight portions and curves, the curved portions in part diverging from a single vertical plane and being inclined so that one step section will lap another in passing around the curve, substantially as described.

3. The combination in a moving stairway, of straight and curved guides forming an endless path, a series of step sections forming an endless chain, each step section being rectangular, the carrying run of the step sections being straight and exposing the full tread of the step sections, the curved sections being arranged on such an incline that one step section will lap another obliquely in passing around the curve, substantially as described.

4. The combination in a moving stairway, of straight ascending and descending runs connected by curved runs, step sections arranged to travel on said runs, and each pro-

vided with risers extending from its longitudinal edges the curved portions of the runs being so shaped that one step section will lap another obliquely in passing around the 5 curve, substantially as described.

5. The combination in a moving stairway, of straight ascending and descending carrying runs, curved connecting runs, rectangular step sections arranged to travel on said runs, 10 the curved connecting runs being depressed to allow one step section to overlap another obliquely in passing around the curve, substantially as described.

6. The combination in a moving stairway, 15 of straight ascending and descending carrying runs, curved runs and straight horizontal runs connecting the curved runs with the ascending and descending runs, the curved runs being depressed and diverging in part from a 20 single vertical plane, with rectangular step sections arranged to travel on said runs to form steps on the ascending and descending portions of the stairway and platforms at the horizontal portions of the stairway, and arranged 25 to turn the curve by one-step section lapping over another, substantially as described.

7. The combination in a moving stairway, of ascending and descending carrying runs, 30 curved runs connecting the ascending with the descending portion, the platforms for the two runs being on the same plane, the curved portions being depressed, with an endless chain of step sections arranged to travel on the 35 said runs and to overlap each other obliquely as they pass around the curved runs, substantially as described.

8. The combination in a moving stairway, of straight guides and curved lateral guides, 40 step sections arranged to travel on said guides and each provided with a riser or risers extending from its longitudinal edges, the guides being so arranged that each step section will move to a position below the succeeding one before it turns, substantially as described.

9. The combination in a moving stairway, of ascending and descending guides, curved guides connecting the said ascending and descending guides, said curved guides consisting of two oppositely inclined sections and a horizontal section, with step sections arranged to travel on said guides, and means for driving the step sections, substantially as 55 described.

10. The combination in a moving stairway, of inclined ascending and descending runs, with curved lateral connecting runs, a portion of the curved connecting runs being also 60 on an incline, the degree of inclination of the connecting run being greater than that of the ascending or descending run, with step sections arranged to travel on said runs and to turn one clear of another on the curved portions, substantially as described.

11. The combination in a moving stairway, of inclined ascending and descending runs, curved lateral connecting runs depressed, the degree of inclination of the depressed portion of the curved runs being greater than that of the ascending or descending runs so that while the step sections will not clear each other on the ascending or descending runs they will clear each other on the connecting runs, substantially as described. 70

12. In a moving stairway or the like, the combination of a series of carriages or steps, straight or substantially straight inclined and horizontal tracks for the support and guidance of the carriages or steps when in use, 80 and lateral loops consisting in part of spirally curved tracks connecting said straight tracks into an endless way, and means for driving the carriages or steps. 75

13. In a moving stairway or the like, an endless track for the step sections consisting of straight inclined and horizontal sections connected by loops, each loop comprising two spiral segments, and on either side of said segments, a straight section of inclined track, 90 and a section of horizontal track between the inclined sections that are intermediate of the spiral segments, substantially as described. 85

14. In a moving stairway or the like, the combination of an endless way consisting of 95 straight inclined and horizontal portions and the necessary lateral curves to make a complete circuit, a series of carriages or steps, means connecting said carriages or steps permitting of movement in both horizontal and vertical planes, devices for locking the carriages or steps against lateral movement on the straight incline, on the straight horizontal and also on the curved portions of the way, and means for driving the steps, substantially as described. 100

15. In a moving stairway or the like, the combination of an endless track or guideway comprising inclined and horizontal straight and spirally curved sections, an endless series 110 of step sections supported upon anti-friction devices arranged in an axial line, a post attached to each step section at its center, hubs journaled on the posts, parallel links of constant length journaled at each end upon the hubs, arms projecting from the hubs, sets of abutments on the step sections to coöperate with said arms and lock the steps against swiveling on the posts, one of said sets of abutments being so arranged as to be in contact with said arms while the step sections are traveling in spirally curved paths, and means for driving the 115 step sections, substantially as described. 120

16. In a moving stairway or the like, a step section comprising supporting wheels arranged in a single axial line, a central post on 130

the step section disposed beneath and at right angles to the tread, hubs journaled upon the posts, links journaled upon the hubs, the link farthest from the tread having teeth to engage a driving means, said link being journaled on its hub so as to take a position, when engaged by the driving means, in a line with the axle of the step, whereby the tendency of the driving means to swing the 10 step on its axle is neutralized, substantially as described.

17. In a moving stairway, substantially straight carrying runs, a lateral loop connecting the ends of the carrying runs, said 15 loop comprising a way therefor and a jointed step-like structure arranged to travel on said way, the steps comprising said structure having means whereby their treads are maintained at all times horizontal, substantially 20 as described.

18. In a moving stairway, the combination of a substantially straight carrying run and a concealed inclined lateral loop connecting the ends of the carrying run, the stairway being provided with means for everywhere maintaining its treads horizontal, substantially as described.

19. In a moving stairway or the like, a substantially straight carrying run and an inclined lateral loop connecting the ends of the carrying run, said stairway being provided with means for maintaining the treads thereof at all times horizontal, substantially as described.

35 20. A lateral loop for connecting the ends of the carrying runs of a moving stairway or the like, and comprising two oppositely inclined spiral segments and a straight section intermediate of said spiral segments, substantially as described.

21. In a moving stairway or the like, a lateral curved way forming a loop and connecting the ends of the carrying runs, said curved way comprising two oppositely inclined spiral segments, substantially as described.

22. In a moving stairway or the like, substantially straight carrying runs a lateral loop comprising a spiral segment for connecting the ends of the carrying runs, substantially as described.

23. In a moving stairway or the like, carrying runs, a lateral loop connecting the ends of the carrying runs, said loop comprising 55 straight inclined, straight horizontal and spirally curved sections, substantially as described.

24. In a moving stairway, the combination of an endless series of step sections, 60 an endless guideway therefor comprising straight inclined and horizontal carrying runs, inclined curved lateral loops connecting the ends of the carrying runs, and means for guarding the steps from use when on the 65 loops, substantially as described.

25. In a moving stairway or the like, comprising an endless series of step sections including substantially straight carrying runs and means for maintaining the treads everywhere horizontal, lateral loops connecting the ends of the carrying runs and step sections on the loops, with treads disposed in parallel planes and guarded from use by passengers, substantially as described.

26. In a moving stairway or the like, the combination of the pair of rails arranged in straight inclined and horizontal carrying runs, and straight inclined and horizontal and spirally curved loops, of the step sections having a single bearing support upon each rail, the parallel linkage system to hold the tread surfaces of the step sections horizontal on all portions of the track, and means for driving the step sections, substantially as described.

27. In a moving stairway or the like, the combination of an endless series of step sections, each having a rectangular tread, an endless guideway comprising straight inclined and curved inclined portions, means for retaining the tread surfaces of the step sections in parallel horizontal planes when on said inclined portions, the step sections on the straight incline having their longitudinal axes in parallel planes, and those on the curved incline being disposed with their longitudinal axes in planes oblique to each other, and means for driving the step sections, substantially as described.

28. In a moving stairway or the like, the combination of an endless series of step sections, each having a rectangular tread and a symmetrically curved convex riser, means for everywhere retaining the tread surfaces of the step sections horizontal, an endless guideway comprising a carrying run consisting of straight inclined and horizontal portions, and a lateral loop connecting the ends of the carrying run, said loop comprising straight inclined and horizontal portions and also spirally inclined portions, and means for driving the step sections, substantially as described.

29. In a moving stairway or the like, the combination of an endless guideway comprising a carrying run consisting of inclined and horizontal portions arranged in a straight or substantially straight line, and a loop connecting the ends of the carrying run, said loop comprising straight or substantially straight inclined and horizontal portions, and also a spirally curved portion, an endless series of step sections each having a substantially rectangular tread and a convex riser whose curvature substantially coincides with the path through which the edge of the adjacent step swings in relation to it while changing from the horizontal to the inclined portions of the straight, or substantially straight part of the guideway, and means for 130

driving the step sections, substantially as described.

30. The combination in a moving stairway, of step sections, posts depending from 5 said step sections, and a series of hubs swiveled on the posts, the upper hub having a lubricant receiver, substantially as described.

31. The combination in a moving stairway, of step sections having depending posts, 10 a series of hubs mounted on the posts, each hub having bearings for a link, and a slot in the upper portion of each hub forming a way for lubricant, substantially as described.

32. The combination in a moving stairway, of a series of step sections, a post ex- 15

tending from each step section, links connecting the several sections, one of said links being in the form of a rack and having a flange forming a lubricant catcher so that any lubricant dripping from the posts will be 20 caught by the receiver, substantially as described.

In testimony whereof, I have signed my name to this specification, in the presence of two subscribing witnesses.

GEORGE A. WHEELER.
